UNITED STATES PATENT OFFICE.

LEROY A. WILLIAMSON, OF BOSTON, MASSACHUSETTS.

PORTABLE ELECTRIC-LIGHT FIXTURE.

1,027,633.

Specification of Letters Patent. Patented May 28, 1912.

Application filed October 13, 1910. Serial No. 586,886.

To all whom it may concern:

Be it known that I, LEROY A. WILLIAMSON, of Boston, county of Suffolk, and State of Massachusetts, have invented certain new and useful Improvements in Portable Electric-Light Fixtures; and I do hereby declare the following specification, taken in connection with the accompanying drawings, forming a part of the same, to be a full, clear, and exact description thereof.

My invention relates to an improved form of portable electric light fixture of the same general character as the fixture forming the subject of my Letters Patent, No. 914,772, dated March 9, 1909.

The objects of the invention are to provide novel means for locking the hub against revolution; to provide a suitable standard for the casing; to provide means for suspending the casing; to provide means for holding the plug rigidly within the casing when not in use; and to provide means for preventing the lamp cord from bending at the point where it is connected to the hub.

To these ends the invention consists in the novel construction, arrangement and combination of parts hereinafter described and claimed, reference being made to the accompanying drawings, in which—

Figure 1 is a top plan view of my novel fixture, showing a portion of the casing broken away and the cord hung over a hook. Fig. 2 is a similar view with the top of the casing removed. Fig. 3 is a plan view of the bottom side of the casing. Fig. 4 is a vertical section through the center of the casing. Fig. 5 is a fragmentary section on line 5—5, Fig. 3. Figs. 6 and 7 are details.

Referring to the drawings, A represents the casing which is made in two sections *a* and *a'* fastened together by screws *c* passing through ears *c'* and *c''* formed on the sections *a'* and *a*, respectively, and also by interlocking ribs *d* and *d'*, as shown in Fig. 4. Molded in the top of section *a* of the casing, which is preferably made of hard rubber or composition, is a perforated metal disk *e* for strengthening said casing and preventing it from warping. The section *a'* is provided with an annular standard or support *b* and a series of hinged legs or supports *b'*, as shown in Figs. 3 and 4.

The sections *a* and *a'* are provided with central openings *f* and *f'* in which is journaled a hub *g* provided with two annular flanges *g''*. In one end of the hub *g* is

mounted an electric light socket *h* to which is connected one end of a quantity of lamp cord *i* wound upon said hub and having its other end connected to an attaching plug *h'*. 60 A plate *j* is secured on the other end of the hub *g* by means of screws *g'*, said plate *j* being provided with a hinged arm *k* carrying a knob *k'* which is arranged to engage an opening *l* when in closed position and is 65 locked therein by means of the spring *l'* formed on the plate *j*, as shown in Fig. 5.

The plate *j* is provided with a series of beveled recesses *j''* in the periphery thereof which are adapted to be engaged by a sliding detent *j'* to lock the hub *g* against rotation in one direction. It will be seen that by reason of the beveled edge of the recesses *j''* the rotation of the hub *g* in the opposite direction will automatically disengage the 75 detent *j'* from said recesses.

The casing *A* is provided with a projecting portion *m* having an opening *m'* in the edge thereof adapted to receive the plug *h'* when said plug is not in use. The movement of the plug into the casing is limited by a stop *n*. The wall of the opening *m'* is furnished with recesses *p* so that the plug may be easily grasped between the thumb and finger when it is desired to remove the 85 plug from the casing. The casing *A* is also preferably provided with a strap *r* for suspending said casing, as shown in Fig. 3. Said strap *r* is passed through an eye *s* clamped between the sections *a* and *a'* of 90 the casing and the ends of said strap are adapted to be fastened together by means of a buckle *r'*. Said strap *r* when unbuckled may be prevented from pulling out of the eye *s* by the band *r''*. It will be seen that 95 when it is desired to suspend the casing *A* the strap *r* may be looped over a hook or similar object as shown in Fig. 3, and that when the device is not in use, the free looped end of said strap may be placed upon a hook 100 *s'*, as shown in Figs. 1 and 4. The device may also be suspended in the manner shown in Fig. 1 by locking the hub *g* against revolution and passing the lamp-cord over a hook *t* which may be upon the wall of a 105 room or upon any article of furniture therein.

In order to protect the cord *i* where it engages the hook *t* from wear, a sleeve *i'* is slidably mounted thereon, so that it can be 110 placed in any desired position.

At the end of the lamp-cord *i* which is

connected with the socket *h*, the covering of said lamp-cord is removed and wound around the socket in the form of a loop *u* to prevent the lamp-cord from bending and 5 breaking at the point where it is connected to said socket.

What I claim as my invention and desire to secure by Letters Patent is:

1. In a device of the character described, 10 the combination, with a suitable casing, of a hub mounted to revolve therein, an electric light socket in one end of said hub, a plate secured to the opposite end of said hub and provided with a recess in its periphery, 15 a detent mounted to slide in said casing and adapted to engage and disengage said recess, a quantity of lamp cord wound upon said hub and connected at one end to said light socket, and an attaching plug connected to the other end of said cord.
2. In a device of the character described, 20 the combination, with a suitable casing, of a hub mounted to revolve therein, an electric light socket in one end of said hub, a plate secured to the opposite end of said hub and provided with a series of tapered recesses in 25 its periphery, a detent mounted to slide in said casing and adapted to engage and disengage said recesses, a quantity of lamp 30 cord wound upon said hub and connected at one end to said light socket, and an attaching plug connected to the other end of said cord.
3. In a device of the character described, 35 the combination, with a suitable casing, of a hub mounted to revolve therein, an electric light socket mounted in said hub, a quantity of lamp cord wound upon said hub and having one end connected to said socket, an attaching plug connected to the other end of 40 said cord, means for locking said hub against revolution in one direction, and means operated by the revolution of the hub in the opposite direction to disengage 45 said locking means.
4. In a device of the character described, 50 the combination, with a suitable casing provided with a standard upon one side and an electric light socket upon the other, of a quantity of electric lamp cord within the casing having one end connected to the

socket, an attaching plug connected to the other end of said cord, and means for winding the lamp cord and attaching plug into the casing.

5. In a device of the character described, the combination, with a suitable casing provided with a series of hinged standards upon one side and an electric light socket upon the other, of a quantity of lamp cord 60 within the casing having one end connected to the socket, an attaching plug connected to the other end of said cord, and means for winding the lamp cord and attaching plug into the casing.

6. In a device of the character described, the combination, with a suitable casing, of a hub mounted to revolve therein, an electric light socket mounted in said hub, a quantity of lamp cord wound around said 70 hub and having one end connected to said socket, an attaching plug connected to the other end of said cord, means for locking said hub against revolution, and a slidable sleeve upon said lamp-cord.

7. In a device of the character described, the combination, with a suitable casing, of an electric light socket mounted therein, an attaching plug, a quantity of electric light cord normally within said casing having one 80 end connected to said socket and the other end connected to said attaching plug, and a strap for suspending said casing, said strap being attached at one end to an eye mounted in the casing and having the other 85 end arranged to engage and disengage a hook mounted in said casing.

8. In a device of the character described, the combination, with a suitable casing, of a hub mounted to revolve therein, an electric light socket mounted in said hub, an attaching plug, a quantity of electric light cord normally within said casing having one end connected to said socket and the other end connected to said attaching plug, 90 and means for relieving the strain on the lamp cord at the point where it is connected to the lamp socket.

LEROY A. WILLIAMSON.
